CALENDAR

Malvin Lichter, New Rochelle, N. Y.

Application March 14, 1941, Serial No. 383,312

1 Claim. (Cl. 40—119)

This invention relates to a simplified hanging calendar and more particularly to a calendar having a plurality of pages wherein pages may be rotated to present the selected face of a selected page to view while the top of the calendar carrying advertising matter, pictures or other indicia, may nevertheless also remain in view.

Heretofore in the manufacture of calendars of this type, it has been necessary to slot the calendar sheets themselves and hang the sheets on a card in the form of a hanger over which the sheets might be rotated. The hanger, in this case, was necessarily much smaller than any of the calendar sheets and was of greatly restricted width with respect to the width of the sheets.

An object of the present invention is the provision in a hanging calendar pad having a plurality of reversible pages of means permitting the rotation of the pages to present a selected face of a selected page to view without covering up the card from which the calendar is hung.

There are many other objects of my invention which in part will become apparent, and where not apparent, will be pointed out, in connection with the following specification and drawing, in which:

Figure 1 is a plan view of a pair of blanks which may be used to form the calendar structure of Figure 2.

Figure 2 is a view in perspective of the form of calendar structure utilizing the blanks of Figure 1.

Figure 3 is a cross-sectional view taken along line 3—3 of Figure 2.

Figure 4 is a plan view of a blank for use in the formation of the calendar structure of Figure 5.

Figure 5 is a view in perspective of a modification of a hanging calendar pad.

Figure 6 is a cross-sectional view taken along line 6—6 of Figure 5.

Referring now to Figures 1, 2 and 3, there is here shown a calendar pad having a support card 70 upon which any advertising matter or other indicia may be placed, the said card having a suitable perforated or grommeted hole 21 by which the same may be hung on the wall.

The bottom of the card is provided adjacent the lower horizontal edge thereof, with a slot 72 through which the calendar sheets may be passed in order to reverse the same in a manner hereinafter to be described.

A calendar pad 30 as shown in Figures 2 and 3 may be attached in any suitable manner, as

hereinafter more specifically described, at the bottom of the card 70 beneath the slot 72. When the pad 30 of calendar sheets is secured to the card 70, it is secured in such manner that all of the calendar sheets may then be passed through the slot 72 in the manner shown in Figure 2 (and especially in Figures 5 and 6), so that the same may hang down on either side.

When it is desired now to present one of the 10 interior sheets of the pad to view, it is simply necessary to pass the ends of the sheets above said interior sheet through the slot 72 and pull the said sheets through the slot so that they hang down on the rear side of the card. In this manner, by passing each of the sheets successively through the slot, each corresponding face of each sheet is visible from one side of the pad. By reversing the calendar pad opposite sides of each of the sheets may be presented to view.

In this manner, the pages of the calendar may be turned and each of the sheets reversed so that six pages may be used for a calendar showing twelve months on twelve sides of the sheets; and 25 also the pages may be turned and the calendar reversed so that the months may be successively brought into view without covering up any portion of the card 70 which bears the advertising matter, pictures or other indicia.

Where it is desired to use twelve separate 30 sheets for the twelve separate months, then the reverse side of each sheet may carry any suitable matter such as recipes or directions of various kinds. In such case, the calendar sheets may 35 still be turned and the individual pages carrying any useful information preserved, without tearing any of the sheets from the calendar and without covering up any portion of the card 70 which it is desired to leave uncovered.

40 This represents a distinct advance over prior elements which have necessitated either the tearing of the calendar sheets from the calendar pad or the covering up of the advertising matter on the card to which the calendar pad is attached; or which, in the alternative, have necessitated the mounting of the sheets on a loose hanger so that the calendar sheets may be detached from the card or hanger, the page thereof suitably turned, and then the pad placed once more 45 on the hanger.

In Figures 1 to 3 inclusive, I have shown a form which serves to center the end of the calendar pad 30 in the base of the slot and thus makes the pages of the calendar pad hang evenly on either side of the card. The card 70 of Figures

1 and 2 is provided with a cut-out at 71, the upper surface of which cut out forms the upper surface of the slot 72 in the finished card.

An additional strip 73 is provided having a bend line 74 and having cut-outs 75, 75 which cooperate with the cut out 71 of the card 70 to form a slot 72, when the strip 73 is mounted in place.

The fold line 74 of the strip 73 is placed adjacent the bottom end of the card and the two sections on either side of the fold line are then secured, preferably by adhesive, to the opposite surfaces of the card 70, thus completing the slot in the manner shown. Before the strip 73 is secured in place, the end 76 of the calendar pad 30 may be placed adjacent the fold line 74 and 10 adhesively secured between the two folded up sections of the strip 73, and then the remaining portions of the strip 73 may in the manner previously described, be secured to the card 70.

In this construction the end 76 of the calendar pad is located along the center of the strip so that the pages may fall evenly on either side of the sheet when they are drawn through the slots.

In Figures 4 to 6 inclusive, I have shown a 25 modification of the construction of Figures 1 to 3 inclusive, where the slot previously described is used in the same way in connection with a calendar pad but where additional framing means are provided for any photographs, pictures or 30 advertisements which may be desired on the card, said framing means providing a frame for subject matter on each side of the card.

In Figures 5 and 6 I have shown a card 80 having a plurality of laminations, each of which is cut out at 81 so that a photograph, a picture or any other suitable advertising matter which is slightly larger than the cut-out 81 may be placed between the laminations and framed thereby. The card 80 in this case may preferably 35 be formed from the integral blank of Figure 4 which comprises sections 83 and 84 which are hingedly connected to each other along the fold line 85 which forms the top of the card.

Perforations 86, 86 in the sections 83 and 84 register with each other when the card is folded up to form the mounting means therefor. Cut-outs 81, 81 also register with each other for purposes previously described. A slot 87 is provided in lamination 84; cut-out 88 in lamination 83 registers with the upper portion of slot 87 and helps to define and reinforce the slot 87; lamination 84 is separated by fold line 89 from the extension 90. The fold line 89, when the card is

5 folded about the fold line 85, registers with the edges 91 of the section 83 and extension 90 is then folded up so that cut-out 92 therein registers with the bottom of the slot 87, thus completing the slot and the card.

Before the card 80 is folded up in the manner thus described suitable pictures, photographs or advertising matter may be secured to the sections 83 and 84 of the card so that they register with the cut outs 81 and so that the same will be framed thereby in the completed card.

Also, before the card is folded up and secured in position, the end 94 of the pad 30 is placed adjacent the fold line 89 and the extension 90 is folded up sufficiently to secure the said pad in place. The folding and securing operation is then completed and the card is ready to hang upon a wall.

Here again, the manner of securing the pad in the card is such that the end of the pad extends along the center of the card rather than on one side thereof and thus the pages of the pad may hang evenly on either side of the card.

In the foregoing I have described my invention and a series of embodiments, all of which have in common the placement of the slot in the bottom of the card adjacent the binding means which secures the pad to the card and which permits selected pages of the pad to be drawn through the slot in order to selectively displace either side of the page while at the same time exposing the entire card to view.

Various means have been illustrated which effectively serve to accomplish this result. Many other modifications will, however, be obvious to those skilled in the art, and I prefer not to be bound by the specific disclosures herein, but only by the appended claim.

I claim.

40 As an article of manufacture, a calendar having a support card, means at the upper end of said support card for suspending the same, and a slot near the lower end of said support card; a calendar pad secured to the portion of the support card beneath the slot, the free ends of the 45 pages of said calendar being movable through said slot, the means for securing said pad to said card comprising an adhesive strip bendable over the lower edge of said card and securable in surface-to-surface relation with each surface of said card, said adhesive strip engaging the bound end of the pad, said adhesive strip being also formed to define the slot at the lower end of said card.

MALVIN LICHTER.
